UNITED STATES PATENT OFFICE.

RUDOLF ROSNER, OF CHICAGO, ILLINOIS.

ELECTRIC GAS-GENERATOR.

1,390,646.

Specification of Letters Patent. Patented Sept. 13, 1921.

Application filed January 28, 1921. Serial No. 440,611.

To all whom it may concern:

Be it known that I, RUDOLF ROSNER, a citizen of the United States, residing in the city of Chicago, in the county of Cook and 5 the State of Illinois, have invented certain new and useful Improvements in Electric Gas-Generators, of which the following is a specification, reference being had to the accompanying drawings, forming a part 10 thereof.

The general purpose of this invention is the same as that of my prior invention represented by my pending application, Serial No. 389,684, filed June 17, 1920,—namely, to 15 provide an apparatus for generating a germicidal gas or gases by electrical means. The present invention represents certain developments and improvements of the apparatus shown in my said application as hereinafter described and shown in the drawings and as indicated by the claims.

In the drawings:—

Figure 1 is a medial section of the gas generating machine being taken at parting 25 plane of the two halves of the casing as indicated at line 1—1 on Fig. 2.

Fig. 2 is a transverse section of said machine taken as indicated at line 2—2 on Fig. 1.

30 Fig. 3 is a wiring diagram of the apparatus showing the electrical connections and showing the gas generating machine itself in plan.

Fig. 4 is a plan view of an adjustable 35 drive coupling for the gas generator.

Fig. 5 is an elevation of said coupling taken partly in section.

Fig. 6 is a transverse section taken as indicated at line 6—6 on Fig. 5.

40 In Figs. 1 and 2 I have illustrated the essential unit of my apparatus which may be termed the gas generating machine and corresponds with a similar unit in my aforesaid earlier application. It consists of a casing,

45 1, formed in two halves of dielectric material and having within it a shallow circular recess, 2, with an enlarged portion, 3, extending circumferentially with respect to said recess and constituting the gas generating chamber. Mounted for rotation within the recess, 2, is a disk, 4, of dielectric ma-

terial carrying one or more metallic electrodes, 5, which coöperate with fixed electrodes, 6, situated adjacent one end of the gas generating chamber, 3. This end is 55 provided with an inlet port, 7, in which there is secured a fitting, 8, comprising a chamber, 9, anterior to the inlet, 7, and a valve guide, 10, which supports an inwardly opening valve, 11, adapted to control admission of air to the chamber, 3, through the inlet, 7. The valve, 11, is normally held seated by a spring, 12, shown as a coiled tension spring having one end secured to the valve, 11, and the other end mounted in 60 a slidably adjustable rod, 13, whereby the tension of the spring, 12, may be altered as desired. In the guide, 10, which is in the form of a cap for the chamber, 9, there are formed one or more air admission ports, 14, 65 giving access to the hollow cylindrical guide body, 15, of the valve, 11, and thence through ports, 16, in said cylindrical body to the chamber, 9, when the valve, 11, is opened. The air is drawn into the chamber, 3, by 70 suction created by a suction blower or other suitable means attached to an outlet, 17, connecting with the end of the chamber, 3, remote from the inlet, 7. Such suction producing device is not shown in the drawings 75 but is clearly indicated in a corresponding relation in my prior application, Serial No. 389,684. Under some conditions it is desirable to admit more air than the adjustment of the spring, 12, will permit in view of the 80 suction available, and for this purpose supplemental admission ports, 18, are provided in the wall of the chamber, 9, and are controlled by a rotatable skirt, 19, of the cap, 10, having apertures, 20, positioned to register with the ports, 18. A handle, 21, may be provided for manual adjustment of this auxiliary air inlet.

The electrodes, 5, on the disk, 4, are formed with conducting arms, 22, secured 95 under the metallic head, 23, of the shaft, 24, and said shaft has a portion, 25, running in contact with a brush, 26, which is connected to one of the terminals of a transformer. The other terminal of the transformer is 100 connected to the fixed electrode, 6, by means of a suitable conductor, 27, indicated in

Figs. 1 and 3. By producing an electric discharge between the electrodes, 5 and 6, in the chamber, 3, I am able to produce from the air fed into the chamber through 5 the inlet, 7, a germicidal gas whose nature and quality I am able to vary by certain adjustments in the apparatus about to be described.

The electrical energy for the discharge in 10 the chamber, 3, preferably originates as an alternating current generated by an alternator which may be of the single phase type and is indicated at 28 in Fig. 3. This alternator, 28, is connected into the primary circuit, 29, of a transformer whose secondary circuit, 30, includes the conductors, 26 and 27 and the electrodes, 5 and 6. The shaft, 24, carrying the disk, 22, and electrodes, 5, may be rotated by any convenient means but 15 should be rotated at such a speed that one of the electrodes, 5, will travel past the electrode, 6, during each cycle of the alternating current in the primary circuit, 29. This is very simply accomplished by arranging the alternator, 28, in axial alignment with the shaft, 24, and coupling the shafts of the two machines together as indicated diagrammatically at 31 in Fig. 3. Preferably a 20 coupling member, 32, of dielectric material 25 is used as in a similar situation in the apparatus shown in my prior application above mentioned. If the alternator, 28, be a single phase machine, it will then be evident that the number of electrodes, 5, should not exceed 30 half the number of poles of the alternator in order that there shall be only one discharge between the electrodes, 5 and 6 35 for each cycle of the alternating current. It is also important that the discharge shall 40 occur within a period of time not greater than one-half the cycle so that it shall be completed while the current surge continues in the same direction,—that is before the reversal of the direction of flow of the alternating current. This is readily possible 45 where the alternator and the gas generator are direct-connected as indicated in Fig. 3.

In operating an apparatus of this kind and providing in the casing, 1, an observation window, 33, opposite the fixed electrode, 6, and extending for some distance therefrom I find that as the disk, 4, is revolved in the direction indicated by the arrow, 34, an electric discharge occurs as each of the 50 electrodes, 5, passes the fixed electrode, 6. This begins with a silent static discharge occurring as the electrode, 5, approaches the electrode, 6, and usually about the point indicated at *a*, on Fig. 1. Then follows a 55 regular static discharge from the inclined surface of the electrode, 6, at *b*, with a continuing violet discharge at *c*, along the portion of the fixed electrode which is shaped parallel to the path of rotation of the moving electrode. As the moving electrode 60

leaves its position of closest proximity to the fixed electrode a dynamic discharge occurs and the static discharge is drawn out into a violet stream of sparks indicated at *c*¹. Radially beyond this violet stream or 70 flame is a rather colorless flame extending somewhat indefinitely and indicated by the outline, *d*, while just above the stream, *c*¹, and close to the electrode, 6, may be observed the incandescent dynamic spark at *e*. 75 This flame I find results in the decomposition of the air and its recombination into a gas whose chemical constituency I am at present unable to state but which is found to have quite remarkable healing properties 80 when applied to tissues of the human body whether infected, inflamed or diseased through the presence of germs, particularly those recognized as tubercular.

I have further discovered that by providing a pole changing switch in the secondary circuit, 30, of the transformer as indicated at 35 so that the current surge in the secondary circuit will pass between the electrodes, 5 and 6, in the opposite direction 90 when the pole changer, 35, is shifted, I secure a flame of quite different appearance in which the violet color remains bound closely adjacent the dynamic spark, *e*, at the electrode, 6, instead of being drawn into 95 a flame as indicated at *c* in Fig. 1. And I find that the resulting gas produced by this electric discharge is of a different nature from the gas produced by the flame first described. The former gas corresponding 100 to the flame shown in Fig. 1 has a taste when inhaled which is distinctly bitter and when the gas is injected into water the taste of the water is found to be flat; on the other hand when the current is reversed by the 105 switch, 35, the resulting gas has a taste which may be described as dry but not bitter and the healing effect on a given patient or under certain conditions is found to be different from that of the first gas. 110

As another means of accomplishing this reversal of the current surge in the circuit which includes the electrodes, 5 and 6, I may provide a special coupling member, 32^a, as shown in Figs. 4, 5 and 6, having a slide- 115 able key, 36, adapted to engage one of the notches, 37, in the coöperating member, 38. These notches, 37, are shown in the drawing as actually 180° apart but it is only necessary that they be 180 electrical degrees 120 apart with respect to the alternator, 28, so that the angular relation between the electrodes, 5, and the poles of the alternator, 28, will be changed by the amount of one-half cycle of the alternator if the key, 36, be re- 125 moved from one of the notches, 37, and the clutch member, 32^a, rotated for insertion of the key in the other notch, 37. Obviously this will have the effect of causing the electrical discharge to occur during the other 130

half of the cycle when the current surge in the primary circuit, 29, is oppositely directed and is causing a correspondingly opposite surge of high potential in the secondary circuit, 30. The final effect therefore is to reverse the direction of discharge as between electrodes, 5 and 6, just as when the pole changer, 35, is used.

As a means for modifying the quality of 10 the gas produced in the chamber, 3, I may provide an impedance coil, 39, in the primary circuit, 29, and a switch, 40, by which the impedance coil may be included in series or omitted from the primary circuit at will.

15 The insertion or omission of the impedance or any other method of controlling the quantity of energy represented by the discharge between electrodes, 5 and 6, (as for example substituting an alternator at 28 of higher or

20 lower voltage) seems to affect the quality but not the nature of the gas so that its observable effects on the human tissues are more or less rapid or more or less pronounced.

25 It is my belief that the treatment of the air entering the chamber, 3, at the inlet, 7, and coming in contact with the electric flame results in supercharging the resultant gas with electrons and that the presence of

30 the electron charge is largely responsible for the beneficial effects observed when the gas is used in the treatment of disease. One method of utilizing the gas is to have the patient inhale it as it is drawn from the

35 generating chamber, 3, and I find that by extending a conductor from any convenient metallic portion of the machine such as the supporting frame not shown, and applying the free end of the conductor to the patient's

40 body I am able to control the effect of the gas by localizing it. This may be accounted for by supposing that the gas itself serves as one conductor for discharging static electricity while the conductor which I connect

45 to the machine operates to complete a path for the static discharge which has a controlling effect upon the delivery of electrons into the human system and therefore upon the healing effect of the treatment.

50 As shown in Fig. 1 I prefer to form electrodes, 5, with beveled or inclined surfaces, 5^a, constituting the trailing portions of said electrodes and to form the fixed electrode, 6, with a surface, 6^a, which is inclined toward

55 the path of rotation of the moving electrodes, 5, (considering their direction of travel) and connects with a part, 6^b, which is substantially parallel to said path of motion. This inclination of the surface, 6^a,

60 results in a gradual approach of the electrodes and a gradual narrowing of the air gap so that the static discharge is distributed over a considerable period of time and I avoid the danger of undue shock to the

65 transformer and conductors such as would

result from too sudden and violent static discharge. The tapering or beveling of the surface, 5^a, of electrodes, 5, in a corresponding manner results in a gradual widening of the air gap as the moving electrodes recede from the fixed electrode with the result that the static discharge and the flame at c¹ are drawn out through a longer arc than when the air gap is more abruptly widened.

70 I claim:—

1. In a gas generating machine comprising a chamber of incombustible dielectric material with an inlet, an outlet, a fixed electrode in the chamber adjacent the inlet, a movable electrode mounted to travel past 80 said fixed electrode with a gap between them, means for feeding air through the inlet and a source of high potential electric current connected to said electrodes; means for controlling admission of said air through 85 the inlet comprising an inwardly opening valve with a spring tending to hold it seated and an adjustable mounting for said spring adapted to vary its strength.

2. In a gas generating machine comprising a chamber of incombustible dielectric material with an inlet, an outlet, a fixed electrode in the chamber adjacent the inlet, a movable electrode mounted to travel past 90 said fixed electrode with a gap between 95 them, means for feeding air through the inlet and a source of high potential electric current connected to said electrodes; a chamber anterior to the inlet with an inwardly opening spring seated valve admitting air 100 to said chamber and an auxiliary air admission port for the chamber disposed between said valve and the inlet with a manually adjustable closure for said port.

3. In the combination defined in claim 1, 105 a chamber anterior to the inlet and interposed between the latter and said spring-controlled valve with an auxiliary air admission port disposed between said valve and the inlet and a manually adjustable 110 closure for said port.

4. In a gas generating machine comprising a chamber of incombustible dielectric material with an inlet, an outlet, a fixed electrode in the chamber adjacent the inlet, 115 a movable electrode mounted to travel past said fixed electrode with a gap between them, means for feeding air through the inlet and a source of high potential electric current connected to said electrodes; the surface of 120 the movable electrode which passes adjacent the fixed electrode being inclined to its direction of motion, diverging from the fixed electrode rearwardly with respect to said direction, to gradually widen the gap between them as the moving electrode recedes.

5. In a gas generating machine comprising a chamber of incombustible dielectric material with an inlet, an outlet, a fixed electrode in the chamber adjacent the inlet, a 130

- movable electrode mounted to travel past said fixed electrode with a gap between them, means for feeding air through the inlet and a source of high potential electric current connected to said electrodes; the trailing portion of the movable electrode which passes adjacent the fixed electrode being inclined divergently from said fixed electrode rearwardly with respect to its direction of motion for gradually widening the gap as the moving electrode recedes.
6. In a gas generating machine comprising a chamber of incombustible dielectric material with an inlet, an outlet, a fixed electrode in the chamber adjacent the inlet, a movable electrode mounted to travel past said fixed electrode with a gap between them, means for feeding air through the inlet and a source of high potential electric current connected to said electrodes; the surface of the fixed electrode which stands adjacent the path of the traveling electrode being inclined toward said path with respect to the direction of travel for gradually narrowing the gap as the moving electrode approaches.
7. In a gas generating machine comprising a chamber of incombustible dielectric material with an inlet, an outlet, a fixed electrode in the chamber adjacent the inlet, a movable electrode mounted to travel past said fixed electrode with a gap between them, means for feeding air through the inlet and a source of high potential electric current connected to said electrodes; a part of the fixed electrode surface which stands adjacent the path of the traveling electrode being inclined toward said path with respect to the direction of travel and continuing in a portion substantially parallel to said path of motion.
8. In a gas generating machine comprising a chamber of incombustible dielectric material with an inlet, an outlet, a fixed electrode in the chamber adjacent the inlet, a movable electrode mounted to travel past said fixed electrode with a gap between them, means for feeding air through the inlet and a source of high potential electric current connected to said electrodes; the co-acting surfaces of the two electrodes having inclined portions divergent rearwardly from the path of motion of the traveling electrode as and for the purpose indicated.
9. In a gas generating machine comprising a chamber of incombustible dielectric material with an inlet, an outlet, a fixed electrode in the chamber adjacent the inlet, one or more movable electrodes, a source of high potential alternating current connected to said electrodes, a carrier on which said movable electrodes are mounted to pass the fixed electrode at regular intervals for causing periodic electric discharges in said chamber and means for moving the said carrier at a

rate to produce such discharges with a frequency equal to that of said alternating current and means for feeding the air through the inlet.

10. In the combination defined in claim 9, said electrodes being dimensioned to limit the time of such electric discharges to less than a half cycle of the alternating current.

11. In a gas generating machine comprising a chamber of incombustible dielectric material with an inlet, an outlet, means for feeding the air through the inlet, a fixed electrode in the chamber adjacent said inlet, one or more movable electrodes and a source of high potential electric current adapted to produce periodic surges of current alternately in opposite directions and connected to said electrodes, a carrier for said movable electrodes adapted to move them past the fixed electrode at regular intervals to cause electric discharges in the chamber and means for timing the passage of the moving electrodes to occur with one-half the frequency of said alternating surges so that all discharges in the chamber will be occasioned by similarly directed surges of current.

12. In the combination defined in claim 11, connections adjustable at will for reversing the direction of the current surge through the electrodes of the gas-generating machine for altering the nature of the discharge flame in the chamber.

13. In a gas generating machine comprising a chamber of dielectric material with an inlet and outlet, a fixed electrode in the chamber adjacent the inlet one or more movable electrodes; a source of high potential alternating current including a transformer and an impedance together with means adapted for connecting the latter at will in series with the primary circuit of the transformer; the secondary circuit being connected to the electrodes of the gas generating machine, a carrier on which said movable electrodes are mounted to pass the fixed electrode at regular intervals for causing periodic electric discharges in said chamber, and means for feeding air to the chamber through the inlet.

14. In the combination defined in claim 9, said source of high potential current comprising an alternator and a transformer, the secondary circuit of the latter including the electrodes of the gas generating machine and the means for timing the electric discharges comprising a mechanical connection between said alternator and the carrier for driving the latter with the former.

15. In the combination defined in claim 14, the number of movable electrodes in a gas generating machine being equal to half the number of poles in the alternator.

16. In the combination defined in claim 14, the alternator having a number of poles

equal to twice that of the movable electrodes or a greater multiple thereof.

17. In the combination defined in claim 9, said source of high potential current comprising an alternator and a transformer with the secondary circuit of the latter including the electrodes of the machine and

a pole changing switch in said secondary circuit.

In testimony whereof I have hereunto set my hand at Chicago, Illinois, this 26th day of January, 1921.

RUDOLF ROSNER.
